[57] CLAIM

The ornamental design for set of dinnerware, as shown and described.

DESCRIPTION

FIG. 1 is a perspective view showing small and large pots, a dinner plate, a sugar bowl, and a casserole dish of a set of dinnerware showing my new design;

FIG. 2 is a perspective view of the items of FIG. 1 as seen from the opposite sides thereof;

FIG. 3 is a perspective view of the items of FIGS. 1 and 2 showing the bottoms thereof;

FIG. 4 is a perspective view showing a cup, a pitcher, a pepper shaker, and a dish with a lid of a set of dinnerware showing my new design;

FIG. 5 is a perspective view of the items of FIG. 4 as seen from the opposite sides thereof;

FIG. 6 is a perspective view showing the undersides of the items of FIGS. 4 and 5;

FIG. 7 is a perspective view of a soup dish, a saucer, a casserole dish, and a salt shaker of a set of dinnerware showing my new design;

FIG. 8 is a perspective view of the items of FIG. 7 as seen from the opposite side thereof;

FIG. 9 is a perspective view of the items of FIGS. 7 and 8 showing the undersides thereof;

FIG. 10 is a perspective view of a dinner plate, a platter, a serving dish, and a pot of a set of dinnerware showing my new design;

FIG. 11 is a perspective view of the items of FIG. 9 as seen from the opposite sides thereof;

FIG. 12 is a perspective view showing the undersides of the items of FIGS. 10 and 11;

FIG. 13 is a perspective view of a saucer for use with the pitcher of FIGS. 4-6, a lid for the platter of FIGS. 10-12, a dessert dish, and two serving dishes of a set of dinnerware showing my new design, each of which is symmetrical such that a view from the opposite direction shows the same features;

FIG. 14 is a perspective view of the items of FIG. 13 showing the bottoms thereof;

FIG. 15 is a perspective view of a circular serving plate, large and small pitchers, and a covered casserole dish of a set of dinnerware showing my new design;

FIG. 16 is a perspective view of the items of FIG. 15 as seen from the opposite sides thereof;

FIG. 17 is a bottom perspective view of FIGS. 15 and 16 showing the lip portion of the pitchers;

FIG. 18 is a bottom perspective view of FIG. 15 and 16 showing the handle portion of the pitchers;

FIG. 19 is a perspective view of another casserole dish of the set of dinnerware similar to that shown in FIGS. 7, 8 and 9 wherein the only difference resides in an alternate arrangement of contrasting color;

FIG. 20 is a perspective view of a set of dinnerware according to this invention; and,

FIG. 21 is a perspective view of the set of dinnerware of FIG. 20 as seen from an opposite side thereof.
